GARMENT HANGER

Original Filed Aug. 24, 1946

FIG. A

INVENTOR.
Walter Ludwig
BY *Oscar Land*
Attorney.

UNITED STATES PATENT OFFICE

2,503,829

GARMENT HANGER

Walter Ludwig, Detroit, Mich., assignor to L. A. Young Spring & Wire Corporation, Detroit, Mich., a corporation of Michigan

Original application August 24, 1946, Serial No. 692,766. Divided and this application July 11, 1947, Serial No. 760,383

5 Claims. (Cl. 223—92)

1

This invention relates to improvements in garment hangers.

This application is a division of application, Serial No. 692,766, filed August 24, 1946, for Method of making yokes for garment hangers which resulted in U. S. Patent No. 2,460,939, dated Feb. 8, 1949.

The main objects of the invention are:

First, to provide a yoke for a garment hanger which is of tubular cross section and is of fibrous material and which is conformed and shaped to provide strength and rigidity and adapted to smoothly engage a garment supported thereon.

Second, to provide a garment supporting member of fibrous material and of tubular cross section having the bottom wall thereof conformed and shaped to facilitate ready connection thereto of garment supporting means to dependingly support a garment from beneath said supporting member.

Third, to provide a garment supporting member of the type above described which facilitates economy of production.

Further objects relating to details and economies of production will appear from the description to follow. The invention is defined in the claims.

A structure illustrating preferred embodiments of the invention are shown in the accompanying drawing in which:

Fig. 1 is a side elevation of a garment supporter embodying my invention.

Fig. 2 is a bottom plan view of the yoke member of the garment supporter.

Fig. 3 is a fragmentary view longitudinally of the garment supporter showing a portion of the yoke member in vertical section.

Fig. 4 is a transverse vertical sectional view of yoke arm on the line 4—4 of Fig. 1.

Fig. 5 is a transverse vertical section of the yoke at the apex thereof on the line 5—5 of Fig. 2.

Referring to the embodiment of the invention illustrated in the drawing, reference numeral 1 designates the yoke of the garment supporter, the yoke being provided with downwardly diverging garment supporting arms 2, and being of tubular cross section and of fibrous material, the yoke 1 at the apex 3 thereof has its underwall 4 upwardly collapsed against the upper wall 5 of the yoke longitudinally centrally thereof to provide a longitudinal central groove-like recess 6 in the underwall as shown in Figs. 2, 3 and 5 to impart rigidity and strength to the yoke at the apex thereof. A suspending hook receiving opening 7 elongated in the direction of the length of the 55

2

yoke and disposed at the apex thereof extends through the upper and lower walls of the yoke and intersects the groove-like recess 6. A suspending hook designated generally by the numeral 8 is provided with a hook portion 9, a shank portion 10 and a yoke supporting looped member 11. The shank portion 10 extends through the elongated opening 7, and the yoke supporting looped member 11 is disposed in the longitudinal groove-like recess 6.

The yoke arms 2 are downwardly bent at their outer ends 12 to smoothly engage the garment at the shoulders thereof. These downwardly bent portions are formed by collapsing the underwall 15 of the yoke longitudinally centrally thereof vertically upwardly in abutting relation with the upper wall of the yoke forming the downwardly opening groove-like recesses 13 in the bottom wall as shown in Fig. 2. These groove-like recesses 20 facilitate bending the end portions 12 into downwardly curved form and impart rigidity and strength to the outer ends of the yoke arms.

The yoke arms 2 intermediate the apex 3 of the yoke and the outer ends 12 of the arms are provided with the openings 14 extending through the lower wall of the arms. These openings are formed by cutting spaced longitudinal slits 15 through the underwall of the yoke arms and collapsing the under wall portion 16 upwardly on the outer sides of the slits, forming the longitudinally extending supporting strands 17 spaced downwardly from the upwardly collapsed portions 16 of the bottom wall of the yoke arms, as shown in Fig. 1. The openings 14 are adapted to receive safety pins 18 or other suitable attaching means for detachably and dependingly supporting a garment from beneath the yoke, the loops or strands 17 constituting means for supporting the safety pins 18 or other attaching means.

The yoke 1 of the garment supporter is formed of a paper tube comprising a plurality of plies or layers 19 convolutely or otherwise wound to tubular formation and cemented or glued together at 20 as shown in Figs. 3, 4 and 5. The tubing in its entirety including all the conforming and shaping operations, as the upward collapsing of the bottom wall at the apex 3, the outer ends 12 of the arms 2 and at 16 on the outer sides of the slits 15 as well as the formation of the groove-like recesses 6 and 13 may be quite promptly performed after the tube has been wound to tubular formation and before the glue or adhesive 20 used in cementing the plies or layers together has set. This, as described in the above mentioned parent application, facilitates slipping of the plies relative to

each other during the conforming and collapsing operation, and permanent retention of the same to the conformed or collapsed shape after the adhesive has set.

The foregoing structures are characterized by their simplicity and the inexpensiveness in the production thereof, the rigidity and strength thereof and their effectiveness in supporting a garment. The structures, are such that they may be readily produced by very simple means and by relatively few easily performed steps.

I have illustrated and described very practical embodiments of my invention. I have not attempted to illustrate or describe other adaptations or modifications of my invention as it is believed this disclosure will enable those skilled in the art to embody or adapt my invention as may be desired.

Having thus described my invention what I claim as new and desire to secure by Letters Patent is:

1. In a garment supporter, a yoke member of tubular cross section and of fibrous material and having downwardly diverging garment supporting arms, the under wall of each of the yoke arms having a pair of laterally spaced slits extending through and longitudinally of the under wall, the under wall on the outsides of said pair of slits being upwardly collapsed to form an opening through the yoke arm for receiving means to dependently support a garment from beneath the yoke member.

2. In a garment supporter, a yoke member of tubular cross section and of fibrous material and having downwardly diverging garment supporting arms, the under wall of each of the yoke arms having a pair of laterally spaced slits extending through the under wall, the under wall on the outsides of said pair of slits being upwardly collapsed to form an opening through the yoke arm for receiving means to dependently support a garment from beneath the yoke member.

3. In a garment hanger, a garment supporting

member of tubular cross section and of fibrous material and having a pair of laterally spaced slits through a wall thereof extending longitudinally of the wall, said wall being inwardly collapsed on the outer sides of said pair of slits to form an opening through the garment supporting member for receiving means for attaching a garment to said member.

4. In a garment hanger, a garment supporting member of tubular cross section and of fibrous material and having a pair of laterally spaced slits through a wall thereof, said wall being inwardly collapsed on the outer sides of said pair of slits to form an opening through the garment supporting member for receiving means for attaching a garment to the garment supporting member.

5. In a garment hanger, a garment supporting member formed of a plurality of plies of paper wound to tubular formation and having adhesive therebetween for securing the same together, the underwall of said supporting member having a pair of laterally spaced slits extending through the underwall, the underwall on the outer sides of said slits being upwardly collapsed to form an opening through said underwall for receiving means to dependently support a garment from beneath said supporting member, the adhesive for connecting said plies of paper setting after upward collapsing of the underwall on the outer sides of said slits to facilitate retention of said underwall in such upwardly collapsed condition.

WALTER LUDWIG.
